HARMONICA CONSTRUCTION

Charles J. Obst, Brooklyn, N. Y., assignor to
 Magnus Harmonica Corporation, Newark, N. J.,
 a corporation of New Jersey

Application October 3, 1951, Serial No. 249,425

4 Claims. (Cl. 84—377)

1

The present invention relates to a harmonica construction and relates more particularly to the manner in which covers are secured to the reed plates and body of a harmonica.

The various objects and advantages of the invention will be apparent and best understood from the following description and the accompanying drawings in which:

Fig. 1 is a plan view of an assembled harmonica embodying the invention;

Fig. 2 is a section view taken along the line 2—2 of Fig. 1;

Fig. 3 is an end view of the cover plate for the harmonica shown in Fig. 1;

Fig. 4 is a view of the reed plate of the harmonica illustrated in Fig. 1; and

Fig. 5 is a section view taken along the line 5—5 of Fig. 4.

Referring to the drawings in detail, there is a body or comb section 10 on each side of which are mounted reed plates 11. Each of the reed plates 11 has a series of openings therein with a reed 12 formed thereon located at each of the openings. The comb section 10 has the usual passageways (not shown) which communicate with the openings and the reeds 12.

A metal cover 13 is attached to each of the reed plates and forms a chamber above the reeds 12. The covers 13 are open along the top edges thereof so as to permit air to pass through the openings in the reed plates and to vibrate the reeds as the harmonica is played. The ends 14 of the covers 13 are flattened and rest on the outer surface of the reed plates 11 at the ends thereof. The cover ends 14 each have an offset tongue or tab 15 stamped therefrom. The tabs 15 are L-shaped and project rearwardly from the inner faces of the ends of the covers.

When the covers 13 are assembled to the reed plates 11, as shown in Fig. 2, the L-shaped tabs extend through openings 16 in the reed plates and into recesses 16a on the inner faces of the reed plates 11. When the tabs 15 are seated in the recesses 16a, projections 17 at the top (or open end) of the cover 13 engage with a lug 18 projecting from the outer face of each of the reed plates 11 at the top edges thereof. The lugs 18 slope downwardly to the reed plate 11 so that the projections 17 will ride over them readily as the covers are put in place and in addition, the flexibility of the reed plates permits them to spring away from the cover as they are assembled.

When the covers are secured to the reed plates in this manner, they are firmly anchored in place without the use of any rivets or screws or other independent fastening means. Following the as-

2

sembly of the cover to the reed plate, the cover and the reed plate may then be assembled to the comb section 10 as a unit. When the reed plate and the comb section are made of plastic materials, as is preferred, they may be assembled by applying a solvent for the particular plastic to one of the parts and then pressing the opposing faces together or they may be secured together by suitable adhesives.

10 After the cover and reed plate have been assembled to the comb section, the reed plate is then rigid and the projections 17 on the cover are locked in engagement with the lug 18 on the reed plate so that the cover cannot be removed without distorting it materially. In addition, the thickness of the tabs 15 on the cover may be slightly greater than the depth of the recesses 16a in the reed plate. The lugs 15 will thus be impressed into and held to bosses 19 at the ends of the comb section when a solvent is used to secure the reed plates to the comb section.

It will be understood that various modifications and changes may be made in the particular embodiment of the invention shown and described herein without departing from the scope of the invention as defined by the following claims.

I claim:

1. In a harmonica, the combination of a comb section, a reed plate secured to the comb section, said reed plate having apertures extending through said plate at the ends thereof and a lug projecting from the outer face thereof, a cover extending over the reed plate, said cover having end portions resting on the ends of the reed plate, offset tongues projecting from the inner surface of the cover at each end thereof, said tongues extending through the apertures in the ends of the reed plate and engaging with the inner face of the reed plate and a projection extending inwardly from the cover, said projection engaging with the lug on the reed plate and preventing movement of the cover transversely of the reed plate.

2. In a harmonica, the combination of a comb section, a reed plate secured to the comb section, said reed plate having apertures extending through said plate at the ends thereof and recesses on its inner face communicating with said apertures, a lug projecting from the outer face of the reed plate at one edge thereof, a cover extending over the outer face of the reed plate, L-shaped tongues projecting from the inner surface of the cover at the ends thereof, said L-shaped tongues extending through the apertures in the reed plate and having portions seating in the recesses communicating with said apertures.

and a projection extending inwardly from the cover along one side thereof and engaging with the lug on the outer surface of the reed plate in opposing relation to the engagement of the L-shaped tongues with the apertures in the reed plate.

3. In a harmonica, the combination of a reed plate having an aperture extending therethrough at each end thereof and a lug projecting from the outer surface thereof, said lug being located at one side of the reed plate, and a cover extending over the outer surface of the reed plate, said cover having inwardly extending L-shaped tongues at the ends thereof and an inwardly extending projection thereon at one side thereof, said L-shaped tongues being positioned to extend through the apertures in the reed plate and to engage with the inner face of the reed plate, said projection being positioned to engage with the lug on the outer surface of the reed plate in an opposing relation to the engagement of the

L-shaped tongues with the apertures in the reed plate.

5. In a harmonica, the combination as defined in claim 3 wherein the reed plate has recesses on the inner face thereof communicating with the apertures therein and portions of the L-shaped tongues on the cover are seated in said recesses.
